UNITED STATES PATENT OFFICE

164,073

FLOOR CLEANING IMPLEMENT

James Teague, Chicago, Ill., assignor to E. L. Bruce Company, Memphis, Tenn., a corporation of Delaware

Application February 21, 1951, Serial No. 14,292

Term of patent 14 years

(Cl. D9—2)

To all whom it may concern:

Be it known that I, James Teague, a citizen of the United States, residing in Chicago, county of Cook, State of Illinois, have invented a new, original, and ornamental Design for Floor Cleaning Implement, of which the following is a specification, reference being had to the accompanying drawings, which form a part thereof.

The figure is a front perspective view of the floor cleaning implement showing my new design.

I claim:

The ornamental design for a floor cleaning implement, as shown.

JAMES TEAGUE.
